UNITED STATES PATENT OFFICE.

RAPHAEL AUSTRIAN, OF READING, PENNSYLVANIA.

APPARATUS FOR CLEANING AND POLISHING BOOTS AND SHOES.

SPECIFICATION forming part of Letters Patent No. 290,886, dated December 18, 1883.

Application filed May 23, 1883. (No model.)

To all whom it may concern:

Be it known that I, RAPHAEL AUSTRIAN, a citizen of the United States, residing at the city of Reading, county of Berks, and State 5 of Pennsylvania, have invented a new and useful Improvement in Boot and Shoe Cleaning and Polishing Machinery, of which the following is a specification.

My improvement relates to a self-contained 10 light machine adapted to be operated by the hand, foot, or belt from any suitable power.

The object of the improvement is to furnish 15 the fraternity of boot-blacks and the general public with a machine simple in its construction and inexpensive in cost, that will perform the laborious work of cleaning and polishing with ease, rapidity, and effectiveness. This result is attained by the use of my invention 20 in the form shown in the drawings herewith, forming a part of this specification, similar parts of which are marked with corresponding letters throughout.

Figure 1 is a front elevation of the machine. Fig. 2 represents the right-hand end of the 25 machine, showing foot-power attachment. Fig. 3 is a plan of the base, and a section of the frame just above the same. Fig. 4 is a detached view of the side or cleaning brushes upon the lower spindle. Fig. 5 represents the 30 elastic foot-rest.

A represents the frame, of the form shown, having foot A', center heads, A², offset bend A³, center pivots, A⁴, bearing A⁵, and cross-brace A⁶. The base—a thin hollow casting—is represented by B, and is provided with a raised 35 receptacle, C, for the foot-rest D, resting upon springs E, or the equivalent therefor. F represents a band-wheel; F', the axis of the same; G, a crank either for hand or treadle connection; H, pitman from crank to treadle; I, the treadle; J, treadle-post secured to the base; K, the driving-band; K', driving-band hook; L L, pulleys on spindles; M, the upper spindle; M', the lower spindle; M², a collar on the same; 45 N, the upper concave polishing-brush; N', the lower cleaning and polishing brush; P P, side cleaning-brushes; P', recess in the same for connection with brush N', being secured thereto by screws.

50 The construction of the apparatus is simple. The frame, as shown, is cast in one piece with foot A' and cross-brace A⁶. The heads A² are

drilled and tapped for the screwed centers A⁴. A shouldered pin or axis, F', is provided for the band-wheel, which is tapped into the frame 55 and the band-wheel bored to revolve free on the same. The frame is also drilled and tapped on the left-hand side for the adjusting center of the lower spindle, and bored for the same on the right-hand side of the frame. The spindles M M' are of suitable size for the work, the upper one, M, having mounted thereon the usual concave polishing-brush and a driving-pulley, L, the ends of the spindle being centered to receive the centers A⁴, the lower spindle, M', adapted for insertion in the frame by being slipped through the right-hand side. The collar M² is then placed thereon, and successively the brushes P N P, the center pivot, A⁴, brought in contact with the center in end 65 of spindle, and the collar M² put in contact with the right-hand side frame and secured in place by a set-screw or pin. The brush N' is then brought centrally over the foot-rest D and secured, the brushes P P being in turn secured 70 to N', the brush N' having projections from each end beyond the bristles, and the brushes P P having recesses P' to fit the same, so that when secured together an unbroken surface of bristles is presented to the boot or shoe being cleaned or polished. The brush N on the upper spindle is secured centrally thereon, and may be of finer quality of bristles than the lower brushes. The spindles M M' may 75 be square where they support the brushes, or, if round, the ends of the brushes would be provided with brushes fitted to the spindles and keyed thereto.

To operate the machine, if the boot or shoe is on the foot of the person, the whole operation of cleaning and polishing would be performed upon the lower spindle. The foot being placed upon the rest D, mounted upon springs, as has been described, and the band-wheel F being driven in any convenient manner, the belt K K', being led upon the pulley L of the spindle M', puts the same in motion, when the foot, being oscillated and vibrated upon the rest, accommodates itself to the several movements, bringing all parts of the boot or shoe 90 in contact with the brushes P N' P, and effectually cleaning the same. Blacking is then applied, and the same process being gone through, the article is polished; but when the machine 95 100

is operated for a hotel, steamboat, &c., the boot or shoe is taken in the hand and presented to the lower brushes for cleaning, and when all cleaned the belt is unhooked and transferred to the upper spindle-pulley, and in turn they are all polished. The spindles M M' are placed exactly the same distance from the axis F'; therefore the band K may be transferred to either spindle-pulley and the same 10 operated by simply unhooking at K', making the change, rehooking, and putting in motion.

I am aware that I am not the first to produce a boot and shoe polishing machine, as there have been a number of the same patented; 15 but to the best of my knowledge all have so far failed of introduction, owing to clumsiness of construction, excessive cost of same, and general incompatibility to satisfactorily do the work required of such a machine. Practically my machine leaves nothing to be desired in its operation, and the cost, as will be evident from the description, cannot be excessive.

Having shown the advantage, construction,

and adaptability of my invention, I desire to 25 secure by Letters Patent the following claims thereon:

1. In a boot and shoe polishing apparatus, as shown, the band-wheel F, placed central to the brush-spindles M M', in combination therewith through pulleys L L, and with brushes N and N' P P through band K K', all adapted to be operated in any suitable manner, whereby either spindle may be driven from the wheel F without change in the length of belt, 30 substantially as described, and for the purpose set forth.

2. The combination, with the concave brush N' of the side brushes, P P, provided with recess P', and the foot-rest D, spindle M', pulley L, band K K', band-wheel F, and suitable power applied thereto, substantially as and for the purpose set forth.

RAPHAEL AUSTRIAN.
